CLAIM

The ornamental design for digital video disc player with tuner and amplifier for automobile, as shown and described.

DESCRIPTION

FIG. 1 is a perspective view of front and right side of digital video disc player with tuner and amplifier for automobile showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view showing another embodiment showing a state that the display is stored.

The portions of the article in broken lines form no part of the claimed design.
